(57) **CLAIM**

The ornamental design for a mobile console, substantially as shown and described.

DESCRIPTION

FIG. 1 is a perspective view of my new design; FIG. 2 is a front view of the design of FIG. 1; FIG. 3 is a rear view of the design of FIG. 1; FIG. 4 is a right side view of the design of FIG. 1; FIG. 5 is a left side view of the design of FIG. 1; FIG. 6 is a top view of the design of FIG. 1; and, FIG. 7 is a bottom view of the design of FIG. 1. The broken lines in FIG. 3 are included for the purpose of illustrating portions of the mobile console that form no part of the claimed design.
